Term of patent 14 years

(Cl. D33—6)

FIG-1

FIG-4FIG-2FIG-3

The back of the chest is conventionally plain while the side not shown is like the side shown.

The dominant features of my design reside in those portions shown in full solid lines.

I claim:

The ornamental design for a chest, substantially as shown and described.
